United States Patent Office.

DAVID HARGAR, OF DES MOINES, IOWA.

Letters Patent No. 70,557, dated November 5, 1867.

IMPROVEMENT IN FURNACE.

The Schedule referred to in these Letters Patent and making part of the same.

TO ALL WHOM IT MAY CONCERN:

Be it known that I, DAVID HARGAR, of Des Moines, in the county of Polk, and State of Iowa, have invented a new and useful Improvement in Furnaces; and I do hereby declare the following to be a full, clear, and exact description of the same, reference being had to the accompanying drawings, forming part of this specification, and in which—

Figure 1 represents a perspective view of my invention attached to a furnace.

Figure 2 shows the construction of that part of the pipe which runs under the fire.

Similar letters of reference indicate corresponding parts in the two figures.

The invention is for the purpose of conducting air from a fan, or from any cold-air region, to a furnace or grate, and distributing it properly to the fire.

In the drawing, D represents the common furnace-walls supporting the boiler E, C being the fire-box, beneath which is the ash-box F.

My invention consists of the pipe A, running from a fan situated in any part of the building, however remote from the furnace, or even in a neighboring building, and extending under and across the fire-box, in the manner shown in the drawing. The upper wall of the pipe, where it extends horizontally across under the fire-box, is perforated with a series of small holes, *a a a*, which have a slide-cover, *d*, by which they may be opened or closed, wholly or partially, as may be required. The extremity of the pipe not attached to the furnace may be connected with a fan, or may extend into a draught of cold air outside of the building, for the purpose of conducting fresh air to the fire. The pipe may be used in connection with the furnaces of manufacturing establishments, large or small, and is equally adapted for application to the common stove, fireplace, &c. By means of it a permanent and equal supply of fresh air is fed to the fire at all times, and in the desired quantities. It is not necessary, with this arrangement, to locate the fan in the immediate vicinity of the furnace, where the room is often necessary for some other purpose; and the fact that it may be placed in any part of the building makes it easy often to effect a great saving, not only of room, but of power, as it may be placed so as to be operated by that shaft which will do it most economically.

Having thus described my invention, what I claim as new, and desire to secure by Letters Patent, is—

The combination of the pipe A, having the apertures *a a*, and provided with the sliding cover *d d*, with the furnace C D F, the several parts being constructed, arranged, and operating together, substantially in the manner and for the purpose specified.

To the above specification of my improvement I have signed my hand this 14th day of May, 1867.

DAVID HARGAR.
